US0D1043179S

(12) United States Design Patent (10) Patent No.: US D1,043,179 S
(45) Date of Patent:  Sep. 24, 2024

(54) CHILD PILLOW

(71) Applicant: Zhejiang Chuanyang New Material Inc., Zhejiang (CN)

(72) Inventor: Ruixi Chen, Fujian (CN)

(73) Assignee: Zhejiang Chuanyang New Material Inc. (CN)

() Term: 15 Years

(21) Appl. No.: 29/805,592

(22) Filed: Aug. 27, 2021

(51) LOC (14) Cl. 06-09

(52) U.S. Cl.

USPC D6/601

(58) Field of Classification Search
